UNITED STATES PATENT OFFICE.

JOHN M. DOHERTY, OF MUNSON, ALBERTA, CANADA.

SCRUBBING-MACHINE.

1,040,172.

Specification of Letters Patent.

Patented Oct. 1, 1912.

Application filed January 26, 1911. Serial No. 604,864.

To all whom it may concern:

Be it known that I, JOHN M. DOHERTY, a subject of the King of England, residing at Munson, in the Province of Alberta, Dominion of Canada, have invented certain new and useful Improvements in Scrubbing-Machines; and I do hereby declare the following to be a full, clear, and exact description of the invention, such as will enable others skilled in the art to which it appertains to make and use the same.

This invention relates to scrubbing machines and has for an object to provide a device of this character that will have novel reciprocating scrubbing brushes that may be readily converted into driers.

A further object of the invention is to provide a novel mechanism for reciprocating the brushes, this mechanism being easily thrown in and out of gear with the ground wheels.

A still further object of the invention is to provide a detachable reservoir that may be manipulated to direct a stream of water in any desired direction.

With the above objects in view the invention consists in the novel details of construction and combination of parts hereinafter fully described and claimed, it being understood that various modifications may be made in the minor details of construction within the scope of the appended claims.

In the accompanying drawing forming part of this specification, Figure 1 is a plan view of the device, Fig. 2 is a side elevation of the device, Fig. 3 is an enlarged longitudinal sectional view taken on the line 3—3 Fig. 1, Fig. 4 is an enlarged cross sectional view taken on line 4—4 Fig. 1, Fig. 5 is a fragmentary view through the clutch.

Referring now to the drawing in which like characters of reference designate similar parts in the various views, 10 designates an axle, the opposite ends of which are equipped with ground wheels 11. The axle is incased in a sleeve 12 which does not rotate with the axle and to which is fixed the side bars of a handle frame 13. The sleeve 12 is made in sections to permit of a bevel gear 14 being slidably fitted on the shaft, this bevel gear being mounted for rotation with the shaft by means of a set screw 15 projecting into a slot 16 formed longitudinally in the shaft. The gear is provided in its hub with a peripheral groove 17, into which loosely fits a finger 18 carried by a

sleeve 19 which is mounted for sliding movement on one of the sections of the sleeve 11 by means of a set screw 20 projecting into a longitudinal slot 21 formed in this section. By manually sliding the sleeve 19 or clutch as it may be called the gear is thrown into and out of mesh with a hereinafter described brush actuating mechanism.

A skeleton frame projects forwardly from the axle, this frame comprising a side bar 22, a front bar 23 and a stub side bar 24, the latter terminating in a vertically disposed elliptical loop 25 which is equipped axially with a journal box 26.

A driven shaft 27 is arranged in parallelism with the side bar 22 and is journaled near its forward end in the journal box 26, the opposite end of this shaft being journaled in a socket 27 formed on the axle 12. The driven shaft is equipped with a bevel gear 28 and is equipped at its forward end with a disk 29 having a crank pin 30 projecting from its front face. A pair of cross braces 31 are fixed to the side bar 22 and are provided with journal boxes 32 which receive the intermediate portion of the driving shaft.

A pair of longitudinal braces 33 are fixed at their opposite ends to the front bar 23 and foremost of the cross braces 31, and these longitudinal braces are provided intermediate their ends with alined journal boxes 34, these journal boxes alining with a journal box 35 carried by the side bar 22. A rod 36 is loosely fitted in the alined journal boxes and terminates at one end in the yoke 37 which pivotally receives one end of a pitman 38, this pitman being connected to the crank pin 30. As the driven shaft rotates, the rod 36 will be reciprocated through the instrumentality of the pitman.

Mounted on the sliding rod 36 is a pair of brushes or brooms 39, and as each broom and its mountings is identical in construction but one will be described. An approximately rectangular bracket 40 is provided with a transverse orifice 41 of sufficient size to loosely receive the sliding rod, and is further provided with a vertically disposed socket 42 that receives the stem 43 of the broom. Set screws 44 are threaded into the bracket and serve to lock the bracket to the sliding rod and the broom to the bracket. By unloosening the broom set screw, the broom may be rotated so as to bear on the floor entirely in a line parallel to the lon-

itudinal axis of the supporting frame or may be rotated to any angular position transversely of this axis. By unloosening the bracket set screw the bracket may be rotated upon the sliding rod so as to cause the broom to incline to any desired position to the surface being scrubbed.

A shallow pan 45 is riveted or otherwise fixed at its center to the point of intersection of the rearmost cross brace 31 and a longitudinal brace 46 which is secured at its opposite ends to the axle sleeve and foremost of the cross braces. This pan loosely receives a bucket 47 having a spout 48 in which is located a slide valve 49 that regulates the discharge of water from the bucket or reservoir as it may be called. The reservoir may be rotated in the pan so as to direct the position of the spout in any desired direction so that the flow therethrough will be directed against any desired portion of the surface being scrubbed. A pair of handles 50 are fixed to the reservoir and form means for removing the reservoir from its supporting pan when necessary.

For supporting the free end of the skeleton frame a caster 51 is secured to the lower portion of the elliptical loop 25, and another caster 52 is secured to the opposite side of the skeleton frame diametrically opposite the caster 51. These casters permit of the machine being readily guided over the surface to be scrubbed and hold the free end of the frame spaced a constant distance from this surface so that brooms may be adjusted to bear with any desired force against the surface.

It will be noted that the brooms are disposed broadside to the longitudinal axis of

the skeleton frame. In this position the brooms act as scrubbers. By giving the brooms a half turn in their sockets they will be disposed broadside to the cross axis of the frame and in this position act as driers. It will be observed that when the brooms are in position to serve as driers, whereby rotating the brackets to any desired extent on the sliding rod, the brooms will be inclined at any desired angular position relatively to the floor so as to bear with greater or less force against the floor as desired during the drying operation.

What is claimed, is:—

1. In a scrubbing machine, a reciprocating rod, a bracket having a transverse orifice loosely receiving said rod, and further provided with a vertically disposed orifice, a broom having a stem fitting in the last named orifice, and set screws adjustably securing said bracket to said rod and said stem to said bracket. 55

2. In a scrubbing machine, a hollow side bar equipped with a vertically disposed closed loop, a driving shaft having a disk within said loop, a pitman on said disk, a reciprocating rod connected to said pitman and extending at a right angle to said side bar, a rotatable bracket on said rod, a broom having a stem loosely fitting in said bracket, and set screws adjustably securing said bracket to said rod, and said stem to said bracket. 60 65 70

In testimony whereof, I affix my signature, in presence of two witnesses.

JOHN M. DOHERTY.
